Specification for Design.

Patented Apr. 1, 1913.

Application filed December 3, 1912. Serial No. 734,794. Term of patent 14 years.

To all whom it may concern:

Be it known that I, MORRIS S. WRIGHT, a citizen of the United States, and residing at Worcester, in the county of Worcester and State of Massachusetts, have invented a new, original, and ornamental Design for Vacuum-Cleaner Nozzles, of which the following is a specification, reference being had to the accompanying drawings, forming part hereof.

In the drawing, the figure is a perspec-

tive view of a vacuum cleaner nozzle, showing my new design.

I claim:

The ornamental design for vacuum cleaner nozzle as shown.

In testimony whereof I affix my signature in the presence of two witnesses.

MORRIS S. WRIGHT.
